UNITED STATES PATENT OFFICE.

LUIGI FONTANELLI, OF FERRARA, ITALY.

PROCESS OF RECOVERING CAFFEIN.

1,273,054.

Specification of Letters Patent. Patented July 16, 1918.

Application filed August 27, 1917. Serial No. 188,507.

To all whom it may concern:

Be it known that I, LUIGI FONTANELLI, a subject of the King of Italy, residing at Ferrara, Italy, have invented certain new and useful Improvements in Processes of Recovering Caffein, of which the following is a specification.

The present invention constitutes a process for the recovery of caffeine from the residues or soot deposits which have formed or collected in the flues of apparatus in which coffee is roasted.

According to the present invention the process consists of extracting caffeine from the said deposits, during which process the caffeine is volatilized into a moving current of air or other gas which is substantially inert, as regards caffeine at the temperature employed, and from which gas current the caffeine is subsequently condensed or deposited, the operation accordingly being one of sublimation of the caffeine.

The operation can be carried out in any suitable sublimation apparatus, capable of being worked within the required limits of temperature.

In the annexed drawing I have shown one form of apparatus for carrying out the processes.

30 Figure 1 is a front view of the apparatus; Fig. 2 is a vertical, longitudinal section on —x—x— in Fig. 1;

Fig. 3 is a detail figure.

As may be seen from the drawing, the illustrative apparatus comprises an ample chamber or furnace 1 fitted with adjustable gas burners 2, which might be replaced by electric resistances or other equivalent heating means; a chamber 3 which may be of less height than the furnace chamber, open at both ends, in which is arranged a horizontally slidable plate or tray 4 containing the aforesaid soot-products of coffee-roasting, which however might also be replaced by coffee itself or cone-waste of low commercial value; a smoke-discharge pipe 5, which may be led to a drying or concentrating box for the purpose of drying the sublimated product or concentrating the mother liquor.

50 The chambers 1 and 3 are fitted with a

door 6 shutting off air and only letting in a small air amount through holes 7 provided in it. The chamber 3 thus works as a retort or distillation oven; the products vaporized therein pass through the outlet 8 into an ample condensing chamber 9 fitted with a chimney 10 and a regulating damper 15.

In order to facilitate the passage of the volatilized products from chamber 3 to condensing chamber 9, a slow-running fan is applied to the chimney 10.

The condensing chamber 9 is fitted with a door 14 and with a removable box 11 the sides of which are made of wire-gauze as per detail Fig. 3, and the chamber 9 also has horizontal wire-gauze partitions 12, for the purpose of retaining and solidifying the caffeine vapors from chamber 3.

The wire-gauze partitions 12 are preferably made of unalterable wire, or of any wire whatever, provided it be plated with an unalterable metal such as for instance nickel or platinum. 13 is a layer of non-conducting material such as fireclay for instance.

The same apparatus can obviously be advantageously used with other material containing caffeine to be recovered. It will also be seen that several such apparatus could be connected with one another in series, the output being thus intensified with a still more so economical industrial result.

I claim:

1. A process of separating caffeine from solid material containing the same, which process comprises heating the caffeine-containing material in a restricted current of gaseous medium, to a temperature capable of vaporizing the caffeine, and condensing the vaporized caffeine from the current of gaseous medium.

2. A process of obtaining caffeine from the soot produced in the roasting of coffee, which comprises heating said soot in a restricted current of a gaseous medium, thereafter cooling the gaseous medium carrying the vaporized caffeine and condensing the caffeine therefrom.

In testimony whereof I have signed my name to this specification.

DR. LUIGI FONTANELLI.
